UNITED STATES PATENT OFFICE.

ROBERT COANE, OF PHILADELPHIA, PENNSYLVANIA.

DESIGN FOR A BOTTLE.

47,355.

Specification for Design.

Patented May 18, 1915.

Application filed March 24, 1915. Serial No. 16,810. Term of patent 14 years.

To all whom it may concern:

Be it known that I, ROBERT COANE, a citizen of the United States, residing in Philadelphia, in the county of Philadelphia and State of Pennsylvania, have invented a new, original, and ornamental Design for Bottles, of which the following is a specification, reference being had to the accompanying drawing, forming part thereof.

a side elevation of a bottle showing my design.

I claim:

The ornamental design for a bottle as shown.

ROBERT COANE.

Witnesses:

H. LLOYD HUGHES,
F. B. LEWALLEN.
